UNITED STATES PATENT OFFICE.

ADANIROM JUDSON GIBBS, OF MENA, ARKANSAS.

DESIGN FOR A BAG.

SPECIFICATION forming part of Design No. 33,350, dated October 9, 1900.

Application filed May 19, 1900. Serial No. 17,318. Term of patent 14 years.

To all whom it may concern:

Be it known that I, ADANIROM JUDSON GIBBS, a citizen of the United States, residing at Mena, in the county of Polk and State of Arkansas, have invented and produced a new and original Design for a Sand-Bag, of which the following is a specification, reference being had to the accompanying drawings, forming part thereof.

Figure 1 is a plan view of a sand-bag, showing my new design. Fig. 2 is an end view of the same, and Fig. 3 is an edge view.

As shown in the drawings, the leading or material feature of my design consists of a substantially-oblong body 1, one end of which is provided with a substantially D-shaped opening 2, forming a handle, which is round in cross-section. The main portion of the bag is substantially elliptical in cross-section and of an elongated ellipse below the opening.

The surface of the bag is substantially smooth, with a faint representation of the interwoven threads of cloth. The upper edge of the bag at the straight side of the opening represents threads, as shown at 3, and the edges of the bag at the opposite ends of the opening are curved outward, as shown at 4, whereby the ends of the handle are flush or continuous with the outer edge of the bag and the entire handle is given a substantially-semicircular appearance.

Having described my invention, what I claim as new, and desire to secure by Letters Patent, is—

The design for a sand-bag, as herein shown and described.

ADANIROM JUDSON GIBBS.
